UNITED STATES PATENT OFFICE.

DOUGLAS C. KELLOGG AND FRANCIS ROCKETT, OF JACKSON, MICHIGAN, ASSIGNEES TO
THE M. & K. CORSET CO., OF JACKSON, MICHIGAN.

CORSET.

1,315,967.

Specification of Letters Patent. Patented Sept. 16, 1919.

Application filed January 21, 1919. Serial No. 272,343.

To all whom it may concern:

Be it known that we, DOUGLAS C. KELLOGG and FRANCIS ROCKETT, citizens of the United States, residing at the city and county of Jackson, State of Michigan, have invented certain new and useful Improvements in Corsets, of which the following is a specification.

This invention relates to improvements 10 in corsets.

The main object of this invention is to provide an improved corset which is suitably stiffened and supported and at the same time has an upper central front portion which 15 yields readily, thereby avoiding discomfort to the wearer.

Further objects, and objects relating to structural details, will definitely appear from the detailed description to follow.

20 We accomplish the objects of our invention by the devices and means described in the following specification. The invention is clearly defined and pointed out in the claims.

25 A structure which is a preferred embodiment of our invention is clearly illustrated in the accompanying drawing, forming a part of this specification, in which:

Figure I is a detail front view of a front 30 lace, front opening corset embodying the features of our invention.

Fig. II is a detail front elevation of a front opening rear lace corset embodying the features of our invention.

35 Fig. III is an enlarged detail horizontal section on a line corresponding to line 3—3 of Fig. I.

Fig. IV is an enlarged detail vertical section on a line corresponding to line 4—4 of 40 Fig. I.

Fig. V is a detail vertical section on a line corresponding to line 5—5 of Fig. I.

In the drawing similar reference characters refer to similar parts throughout the 45 several views, and the sectional views are taken looking in the direction of the little arrows at the ends of the section lines.

Referring to the drawing, 1 and 2 represent the two front body sections of a corset 50 and 3 a narrow closure member between. This closure member is secured to the edge of the section 1 by means of the lacing 4. The section 1 and the closure member 3 have eyelets 5 for the lace. The closure member 55 1 is detachably secured to the section 2 by

the clasps 6 and studs 7 which are mounted on steels 8 as is usual practice. The upper ends of these steels, however, terminate at 9 in a substantially spaced relation to the upper end of the corset, the corset illustrated 60 being a short waist corset, the waist line thereof being indicated by the lacing.

Above the clasps and studs the closure member 3 and the section 2 are detachably connected by means of hooks and eyes, designated generally by the numeral 10. The steels or stiffening members 11 adjacent the edge of the section 1 terminate at 12 in the plane of the upper ends of the clasp and stud steels 8. This is below the bust of the user. 70 The sections are provided with full length stiffening members 13 adjacent these short stud and clasp steels and stiffening member, the same being indicated conventionally. To support this central flexible portion and at 75 the same time permit its ready yielding or flexing we provide diagonally disposed stiffening members 14 which are arranged with their lower ends below the upper ends of the clasp and stud steels and the short stiffening members, respectively, and adjacent the first full length stiffening members and their upper ends in approximately the vertical plane thereof.

In the modification shown in Fig. II the 85 parts are arranged in the same relation, the same being an adaptation of our improvements to a rear lace front opening corset.

We have not attempted to illustrate or describe other modifications or adaptations 90 as we believe the disclosure made will enable those skilled in the art to which our invention relates to embody or adapt the same as may be desired.

We have illustrated our improvements 95 mainly in conventional form and we believe the same will be readily understood.

Having thus described our invention, what we claim as new and desire to secure by Letters Patent, is:

1. In a corset, the combination of the two front body sections thereof and a closure member between with one of its edges laced to the edge of one body section and its other edge detachably connected to the edge 105 of the other body section by fastenings comprising studs and clasps mounted on steels, such studs and clasp steels and an edge stiffening member of the laced body section terminating a substantial distance from the 110

top of the corset and below the bust providing a central flexing portion at the front, said body sections having full length stiffening members adjacent said stud and clasp
5 steels and said short stiffening member, and stiffening members disposed diagonally upward from such full length stiffening members with their lower ends below the upper ends of said clasp and stud steels and said
10 short stiffening member respectively, and their upper ends approximately in the vertical planes thereof.

2. In a corset, the combination of two front body sections and means for joining
15 the same, the stiffening members for said sections adjacent the edge thereof terminating a substantial distance from the top of the corset and below the bust providing a

central flexing portion at the front, said sections having full length stiffening members adjacent their said short stiffening members, and stiffening members disposed diagonally upward from said full length stiffening members with their lower ends below the upper ends of said short stiffening members and their upper ends in approximately the vertical planes thereof. 20 25

In witness whereof we have hereunto set our hands and seals in the presence of two witnesses.

DOUGLAS C. KELLOGG. [L. S.]
FRANCIS ROCKETT. [L. S.]
